UNITED STATES PATENT OFFICE.

P. H. LAWLER, OF ROCHESTER, NEW YORK, ASSIGNOR TO HIMSELF AND
D. W. ROCHE.

IMPROVEMENT IN BARREL-MACHINES.

Specification forming part of Letters Patent No. 58,729, dated October 9, 1866.

To all whom it may concern:

Be it known that I, P. H. LAWLER, of Rochester, in the county of Monroe and State of New York, have invented certain new and useful Improvements in Barrel-Head Cutters; and I do hereby declare that the following is a full, clear, and exact description thereof, reference being had to the accompanying drawings, making part of this specification, in which—

Figure 1 is a top view of my invention. Fig. 2 is a vertical section of the same, taken in the plane of the red line *o* in Fig. 1.

Similar letters indicate like parts in both figures.

This invention relates to that class of barrel-head-cutting machines in which the dishing saw is used; and its nature consists, mainly, in suspending the clamping-collars upon a swinging standard, the axis of which is parallel, or nearly so, with that of the saw, while that of the clamps is arranged about in the same angle with relation to the saw-mandrel as heretofore, and also in so arranging the axis of the frame of the clamps that the gravity of the parts shall cause it to swing to the open position, or away from the saw.

To enable others to make and use my invention, I will describe its construction and operation.

I provide a frame, *A*, of suitable height for the convenience of the operator. The saw mandrel or arbor *B*, I arrange across the corner of the frame, as shown in Fig. 1, in fixed bearings *C*.

The axis of the clamping-collars *D* and *E* is in the top of the standard *F*, which is hung to the frame *A*, as shown in Fig. 2, in such a manner as to cause the clamps to swing from the saw by its own gravity when released by the spring-catch *G* and the lug or clamp *H*.

The shaft *I* is made to slide longitudinally in its bearings *J* and *J'*, and the outer end is provided with a pivoted coupling, by which latter it is connected to the cam-lever *L*; and there being a strong spiral spring, *s*, placed between the journal-box *J'* and the spur-wheel *W*, when the clamp is set, as indicated by the full lines in Fig. 1, this spring *s* is compressed; and, as may be seen, when the frame

F is released by the spring-latch, the spring *s* forces the mandrel back, and by pressing the cam-lever *L* against the face of the inclined plane *M*, the counterbalancing is greatly assisted, and the clutch *a* on the end of the lever catches at the point indicated at *a'*, and secures the frame in that position until it is again thrown forward by the operator, which is usually done by pressing down the lever *N*, Fig. 2, with his foot. The cord or chain *R* runs over the pulley *T* and connects the lever and frame *F*.

The heading-stuff is placed between the collars *D* and *E*, they being spread and in the position indicated by the dotted lines *D'* and *E'*, the lower edge resting upon the gages or dogs *g* and *h*, which only reach to a short distance beyond the face of the collar *D*. The operator then effects the clamping by pressing the lever *N*, as before stated, and as the clamping-frame reaches the position shown by full lines in the drawings the spur-wheel *W* is brought into gear with the feed-wheel *v*. The clamping-collars are thereby rotated, while the saw *P* forms the circle; which being completed, the pin *i* strikes the end of the spring-hook *G* and releases the clutch *H*, when the frame or standard *F* returns to the open position, releasing the formed head, and it drops to the spout *Y*, Fig. 2, by which it is conveyed from the machine.

The feed-wheel *v* is driven by a band on the pulley *p* from a counter-shaft.

The pin *n* in the spur-wheel *W* is placed about opposite to the pin *i*, that unhooks the clamp *H*, and as the frame swings back toward the position of the dotted lines, the pin *n* strikes the face of the inclined plane or cam *m*, and causes the wheel to turn partially around backward until the pin *i* strikes the under side of the latch *G*, so that when the next head is clamped the wheel shall make so much more than a revolution. The object of this is to cause the saw to cut at least the full circle of the head or a little more. The cam *m* is made adjustable, whereby it may be set as desired.

What I claim as my invention, and desire to secure by Letters Patent is—

1. Hanging the clamping-frame *F* upon an

axis arranged diagonally with relation to that of the clamping-collars, and parallel with relation to that of the saw, as and for the purposes set forth.

2. The arrangement of the adjustable tapet-bar or cam *m*, with the pin *n*, substantially in the manner and for the purposes shown and described.

3. The arrangement, with the sliding mandrel *I* in the swinging frame *F*, of the spring *s*, the pivoted lever *N*, and cam *M*, substantially as shown, and for the purposes set forth.

P. H. LAWLER.
